UNITED STATES PATENT OFFICE.

FREDERICK B. HERRIOT, OF MYRTLE BEACH, CONNECTICUT.

WINDSHIELD CLAMP.

Application filed March 14, 1927. Serial No. 175,410.

This invention relates to adjustable windshields for automobiles, particularly to a means for mounting a movable section of this shield so that it may be adjusted, and to improved means for clamping the shield in adjusted positions.

It is an object of the invention to provide an improved support and adjustable clamp for the movable section of a shield which will firmly clamp the shield in adjusted positions, but may be easily and quickly operated to either release or fasten the clamp.

It is a further object of the invention to provide a clamp which will cause no strain on the glass of the shield, and particularly one in which the clamping strain is longitudinally of the support for the glass so that there will be no lateral strain on the frame which might break the glass.

With the foregoing and other objects in view, I have devised the construction illustrated in the accompanying drawing forming a part of this specification. In this drawing,

Fig. 1 is an elevation of a windshield showing my improved clamp applied, the view being that from the driver's position.

Fig. 2 is a partial elevation and partial section of the clamp operating mechanism.

Fig. 3 is a section thereof substantially on line 3—3 of Fig. 2.

Fig. 4 is an end elevation of one of the bearing blocks for the clamp operating mechanism.

Fig. 5 is a section of the frame at one end showing the clamp in elevation.

Fig. 6 is a transverse section thereof substantially on line 6—6 of Fig. 5.

Fig. 7 is a similar section substantially on line 7—7 of Fig. 5.

Fig. 8 is a plan view of one of the clamping members.

Fig. 9 is a side elevation thereof.

Fig. 10 is a plan view of the wedge for operating the clamp.

Fig. 11 is a side view thereof.

Fig. 12 is a section similar to Fig. 5 showing a slightly different way of mounting the clamping elements especially as applied to the shield support for closed cars, and

Fig. 13 is a section substantially on line 13—13 of Fig. 12.

In the drawing as shown in Fig. 1, the front shield is shown somewhat diagrammatically but involves the usual upright supports 12 at the opposite sides in which the

windshield is mounted, comprising usually the lower section 13 and the upper section 14 of glass. The upper of these sections is mounted for adjustment to permit ventilation, and it is mounted to swing about its upper edge. The glass 14 is mounted in a frame 15 usually of sheet metal shaped to provide a groove in which the edges and ends of the glass are inserted, and the upper horizontal member 16 is of a tubular construction, as shown in Fig. 6, provided with downwardly extending side members 17 bent upon themselves to form a groove to receive the edge of the glass.

The clamps for holding the shield in adjusted positions are located at the opposite ends of the upper tubular member 16 and are shown more clearly in Figs. 5 to 11. The clamp proper is mounted within the tubular member, and in order to strengthen the tubular member I preferably insert in each end of the member 16 a tubular section 18 which may be sweated or otherwise secured in position, and provides means for preventing spreading of the tubular member 16 by the action of the clamping elements. The clamp is composed of two members 19 which together are substantially cylindrical and are rigidly mounted in the end member 20 forming a support, which may be an angle iron secured in the tubular upright supports 12, and the clamping members 19 are rigidly secured to this angle member. The clamps may have a square end 21 in the same sized square opening in the member 20, and they may be welded, soldered or otherwise secured in this member. The square section in the square hole will, of course, hold the clamping elements against rotation in the member 20.

Each of the clamping elements is provided with a transverse groove 24 having an inclined cam surface 25 at the bottom thereof, and when they are placed in position these grooves are opposed to each other and they receive the tapered head 26 of the clamp operating member. The head of this member preferably extends in opposite directions from the shank 27 and is substantially wedge shape to provide inclined surfaces 28 on opposite sides thereof adapted to engage the inclined surfaces 25 of the clamping elements. These elements also have on their opposed faces longitudinal grooves 29 to receive the shank 27 of the operating member.

Means for operating the clamp to tighten

or release the same may be located anywhere between the opposite ends of the upper tubular member 16. In the drawing I have shown it at substantially the center of this member where it is easily accessible for operation by the driver, but if some other location is more convenient as one more nearly directly in front of the driver, it can be easily mounted in that position. For the purpose 10 of mounting this operating means the tubular member 16 is notched, as shown at 30. Mounted within the tubular member on opposite sides of this notch are bearing blocks 31 in transverse section substantially the 15 shape shown in Fig. 4, and they each have a longitudinal bearing 32 for a rotatable member 33 which is tapped from its opposite ends with right and left hand threads 34 and 35 for threaded engagement with the threaded 20 ends 36 and 37 of the shanks 27 of the clamp operating members. The two bearing blocks may be secured against movement in the tubular member 16 by transverse screws 38. There is a suitable right angle drive for the 25 rotatable member 33. As shown in the drawing it comprises a worm gear 39 mounted on and secured to the member 33 by any suitable means, such as a pin 40, and this worm gear meshes with a worm 41 on a transversely extending shaft 42. I am not, however, limited 30 to this specific drive as I may use spiral gears, helical gears and the like. This shaft is mounted to rotate in bearings in a pair of members 43 and 44 adapted to be clamped on 35 opposite sides of the tubular member 16 by means of the screws 38. Additional screws 45 may be used to clamp the upper part of the front clamp 43 to the bearing blocks and the tubular element. The shaft 42 and the worm 40 carried thereby may be rotated by a knurled hand knob 46 secured to the shaft by any suitable means, such as a pin 47.

This operating means may be assembled by 45 inserting the bearing blocks 31 from the ends of the tubular member 16 together with the rotatable member 33 and the worm gear 39. When brought into alignment with the notch 50 30 the worm 41 may be placed in mesh with the gear and the two supporting members 43 and 44 applied as described above to hold the worm and its operating shaft in position.

It will be obvious that by rotating the 55 hand knob 46 in one direction it will rotate the worm gear 39 and the member 33. The right and left hand threaded connections of this member with the shanks 27 will shift 60 these members longitudinally of the member 16 either toward each other or outwardly 65 away from each other. If they are drawn toward each other they will slide the tapered heads 26 on the inclined walls 25 of the clamping elements 19. This action will separate these elements securely clamping their 70 outer curved surfaces against the inner sur-

face of the tubular member 18. It will thus be apparent that as the clamping elements 19 are held against rotation this action will firmly lock the frame of the shield and the shield carried thereby against movement. Rotation 70 of the hand knob in the opposite direction will move the tapered heads 26 outwardly and release the clamping elements allowing the shield to be swung to any desired position in which it may again be clamped by 75 turning the hand knob. It is preferred that the clamping elements be provided with a transverse groove 48 to make them more flexible at this point so that the inner ends may be more easily operated in the clamping ac- 80

In the form shown in Figs. 12 and 13 the clamping elements 19 may be inserted in a ring 48, either round, square or other shape seated in a similarly shaped opening or recess in the frame member 49. The ring may be soldered, sweated or pinned in position as by a pin 50. The clamping elements may be held against turning by means of a pin 51.

It will be apparent from the foregoing 90 description that the clamp is very simple in construction and may be easily and quickly operated to either release the adjustable section of the shield or to tightly clamp it in adjusted position. It is especially to be noted 95 that all of the strain or pull in operating the clamp is directly in the axis of the pivot bar 16 and is also entirely longitudinally thereof, so that there is no cramping action on the frame or glass to break it or cause it to be 100 broken from wind strains.

Having thus set forth the nature of my invention, what I claim is:

1. In a windshield mount, a frame for the shield including a tubular member, means at each end of the tubular member to clamp the shield in adjusted position, means within the tubular member and movable longitudinally thereof for operating the clamping means, said tubular member having an opening intermediate the ends thereof, a rotatable member mounted in the tube at said opening and having threaded connection with said longitudinally movable means, a bearing member clamped to the tubular member, a 105 rotatable driving member carried by the bearing member and extending transversely of the tube, a driving connection between the rotatable member and the driving member, and a 110 manual means for operating the driving member.

2. In a windshield mount, a support, a frame for the shield including a tubular member pivoted at its opposite ends on the support, clamping means at said end to hold the member against turning, means within and movable longitudinally of the tubular member for operating the clamping means, a rotatable element intermediate the ends of said member having right and left hand 125

threaded engagement with said operating means, a worm wheel connected to said rotatable member, a worm meshing with said wheel, and a manual means for operating 5 said worm to lock and release the clamping means.

3. In a windshield mount, a support, a frame for the shield including a tubular member, pivot means for the opposite ends 10 of said member including at each end a pair of clamping elements secured to the support and extending into the tubular member, said elements having opposed oppositely inclined surfaces on their adjacent sides, an operating

member having a substantially wedge shaped 15 head between said surfaces and adapted by longitudinal movement to cooperate therewith to separate said elements and clamp them against the tubular member, said operating members each having a threaded 20 shank extending longitudinally within the tubular member, a rotatable member between said shanks and having threaded engagement therewith, and manual means for rotating said member to operate the clamping 25 means.

In testimony whereof I affix my signature.

FREDERICK B. HERRIOT.
